UNITED STATES PATENT OFFICE.

HAROLD J. BELL, OF GLOUCESTER CITY, NEW JERSEY, ASSIGNOR TO THE WELSBACH INCANDESCENT GAS LIGHT COMPANY, OF NEW JERSEY.

INCANDESCENT GAS-BURNER.

SPECIFICATION forming part of Letters Patent No. 400,166, dated March 26, 1889.

Application filed May 10, 1888. Serial No. 273,456. (No model.)

To all whom it may concern:

Be it known that I, HAROLD J. BELL, a citizen of the United States, residing at Gloucester City, in the county of Camden and State 5 of New Jersey, have invented new and useful Improvements in Incandescent Gas-Burners, of which the following is a specification.

This invention relates to incandescent gas-burners; and it consists in a combined gallery 10 and burner adapted for use with a suspended mantle or hood in the Welsbach system of incandescent gas-lighting.

The invention will be more particularly hereinafter described, and then pointed out 15 in the claims.

In the annexed drawings illustrating the invention, Figure 1 is a perspective view of my improved incandescent gas-burner and gallery combined. Fig. 2 is a plan of the 20 same. Fig. 3 is a vertical section of the same with chimney-gallery, chimney, mantle, and mantle-support.

The numeral 1 designates a portion of an atmospheric gas-burner tube having at its 25 upper end a gas and air mixing chamber, 2, inclosing a perforated or gauze diaphragm, 3, above which is seated a burner-tip, 4, provided with a circular series of gas-exits, 5, that open into an annular flame-passage, 6, 30 the construction of these parts being similar to that shown and claimed in an application, Serial No. 266,505, filed by me March 8, 1888.

The burner-tip and upper part of its supporting-tube are surrounded at a suitable 35 distance by a deep annular deflector, 7, which forms, with the outer wall of the burner-tip, an annular chamber to receive and conceal the lower ragged edge or skirt of the mantle 8, which is supported by a rod or wire, 9, as 40 usual. The deflector 7 may be provided with a vertically-elongated and longitudinally-perforated lug, 10, to receive the rod or wire 9, which is held in place at any desired height by means of a set-screw, 11, passed into the 45 lug. Owing to the depth or height of the deflector a much longer lug, 10, can be used than has heretofore been practicable, thereby affording a better support for the wire or rod

9 without detracting from the appearance of the burner. The upper edge of the deflector 50 7 is formed with an inwardly-turned lip, 12, which has a notch, 13, in line with the lug 10, to permit the passage of the mantle-supporting rod or wire.

The lower part of the deflector 7 is provided with an external horizontal flange, 14, and from this flange a series of converging arms, 15, extend downward and terminate in a ring, 16, that is secured to the burner-tube 1 in any suitable manner. It will be observed 60 that the annular deflector 7, with the flange 14 and converging arms 15, constitute a gallery which, through the ring 16 and tube 1, is combined with the burner and practically integral therewith.

A chimney-gallery, 17, of any suitable form, may be slipped over the annular deflector 7 or be secured thereto in any convenient manner, to support a chimney, 18, around the burner and incandescent device.

The diameter of the tube 1 should be sufficient to enable it to be slipped over a suitable atmospheric gas-tube supported by a gas-fixture.

What I claim is—

1. The combination, with a gas-burner tube, of a deep annular deflector surrounding the burner-tip and having converging arms connected with the burner-tube and a vertically-elongated lug perforated longitudinally to receive a rod or wire for supporting an incandescent device, substantially as described.

2. The combination of the gas-burner and its tube 1, the annular deflector 7, having a vertically-elongated and longitudinally-perforated lug, 10, and provided with converging arms 15, connected with the burner-tube, the rod 9, and mantle 8, substantially as described.

In testimony whereof I affix my signature in 90 presence of two witnesses.

HAROLD J. BELL.
